UNITED STATES PATENT OFFICE.

AMOS L. FOREMAN, OF YORK, PENNSYLVANIA, ASSIGNOR TO MILK DEALERS' CRATE CORPORATION, OF WILMINGTON, DELAWARE, A CORPORATION OF DELAWARE.

UNITING WOODEN STRIPS.

1,368,222.

Specification of Letters Patent. Patented Feb. 8, 1921.

Application filed May 12, 1920. Serial No. 380,822.

To all whom it may concern:

Be it known that I, AMOS L. FOREMAN, a citizen of the United States, residing in York, Pennsylvania, have invented certain 5 Improvements in Uniting Wooden Strips, of which the following is a specification.

My invention consists of certain improvements in means for uniting wooden strips where embodied in such constructions, for 10 instance, as box, crate or tank walls, the object of my invention being to provide uniting means which will be simple in construction, easy to install and will firmly and securely unite the wooden strips but at the 15 same time will yield in the event of undue pressure being exerted should the wood become wet and, consequently, swell.

My invention is illustrated, in detail, in the accompanying drawing, in which—

20 Fig. 1 is a vertical sectional view of a set or series of wooden strips, united by means constructed in accordance with my invention;

Fig. 2 is a transverse sectional view on the 25 line 2—2, Fig. 1;

Fig. 3 is a transverse sectional view on the line 3—3, Fig. 1;

Fig. 4 is a perspective view of one element of the uniting means;

30 Fig. 5 is a view similar to Fig. 4 but showing the opposite side of the member therein illustrated, and

Fig. 6 is a vertical sectional view similar 35 to a portion of Fig. 1, but illustrating certain features of construction in greater detail.

Referring, first, to Fig. 1, there is shown a wall built up of wooden strips 1, 4, 5 and 6. Passing longitudinally through axially 40 aligned openings in said strips is a metallic tube 7 preferably of sheet steel, threaded, internally, at its ends for the reception of externally threaded screws 8 and 9. The head of the screw 8 bears against the base of 45 a countersunk opening 8^a in the upper edge of the strip 1 and the head of the screw 9 bears against the base of a corresponding opening 9^a in the lower edge of the strip 6. The four strips 1, 4, 5 and 6 are, through the 50 medium of the tube 7 and screws 8 and 9, firmly and securely united.

The tube 7 is a longitudinally split tube, there being a split 10 traversing it from end to end, as shown in Fig. 4. The reasons for 55 making use of such a longitudinally split

tube are many. First, it is susceptible of easy insertion into the openings in the wooden strips. This may be on account of the fact that the split tube is radially compressible, or the tube may be made a trifle 60 smaller than the openings, in which case the insertion of the screws will be depended upon to radially expand the tube so that it will grip the inner walls of the openings in the wooden strips. Second, to function 65 properly it is necessary that the tube be non-rotatably mounted in the strips. The split tube, of itself, possesses this feature. The edges, at the split 10, bite into the wooden walls of the openings in the strips and 70 thereby resist any tendency, on the part of the tube, to turn. Third, and most important, when used in the construction of the walls of tanks, bottle crates or other articles which, at times, become wet, the split tube 75 enables the uniting means to expand, longitudinally, when the wetting of the wooden strips causes them to so expand that undue pressure is exerted upon the heads of the screws 8 and 9. The manner in which this 80 longitudinal expansion of the uniting means takes place is as follows: As the wooden strips become wet, they expand across the grain, and become, to a greater or less extent, softened and yielding. As the pressure of the cross grain expansion is exerted upon the heads of the screws 8 and 9 the external threads of said screws act camwise, upon the internal threads formed in the inner face of the split tube 7. When the 85 pressure becomes sufficiently great, the tube is expanded radially by this cam action, overcoming the side resistance of the softened and yielding walls of the openings and the strips, thereby permitting either or both 90 of the screws to jump a thread. The longitudinal pressure is thus relieved and the tube again resumes its normal position. The radial expansion of the tube permits jumping of threads without impairment of 95 the latter. Without such radial expansion, threads might, and probably would, be stripped.

Radial expansion of the tube may be facilitated and rendered easier by providing 100 the threaded end portions of the tube with one or more supplementary longitudinal slots 11, as best shown in Figs. 4 and 5.

Jumping of threads may likewise be facilitated and rendered easy by cutting the 110

threads in the inside of the tube 7 to but partial depth, as shown in Fig. 6. In order to permit jumping a less degree of radial expansion of the tube will be necessary than were the threads of full depth.

Of course, should the wooden strips later dry out with consequent shrinkage, it would be desirable to again tighten the screws 8 and 9, which may readily be accomplished.

10 It is, of course, obvious that one of the screws 8 or 9 may be dispensed with, in which case, a bearing head would be formed directly on one end of the tube 7 itself, and the single screw would coöperate with the 15 other end of said tube.

I claim:

1. The combination, in longitudinally expandible means for uniting wooden strips, of a radially expandible metallic tube internally threaded at one end and an externally threaded screw engaging therewith.

2. The combination, in longitudinally expandible means for uniting wooden strips, of a radially expandible metallic tube internally threaded at its ends and externally threaded screws engaging therewith.

3. The combination, in longitudinally expandible means for uniting wooden strips, of a longitudinally split radially expandible

metallic tube internally threaded at one end 30 and an externally threaded screw engaging therewith.

4. The combination, in longitudinally expandible means for uniting wooden strips, of a longitudinally split radially expandible 35 metallic tube internally threaded at its ends and externally threaded screws engaging therewith.

5. The combination, in longitudinally expandible means for uniting wooden strips, 40 of a longitudinally split radially expandible metallic tube internally threaded at one end and an externally threaded screw engaging therewith, said tube having a supplementary split extending longitudinally through the 45 threaded portion thereof.

6. The combination, in longitudinally expandible means for uniting wooden strips, of a longitudinally split radially expandible metallic tube internally threaded at its ends 50 and externally threaded screws engaging therewith, said tube having supplementary splits extending longitudinally through the threaded portion thereof.

In testimony whereof I have signed my 55 name to this specification.

AMOS L. FOREMAN.
